METHOD OF WINDING ARMATURES

Mary M. Hole, Dayton, Ohio, assignor to General
Motors Corporation, Detroit, Mich., a corpora-
tion of Delaware

Application December 29, 1950, Serial No. 203,366

3 Claims. (Cl. 310—203)

1

This invention relates to an improved armature and the method for producing it.

It is among the objects of the present invention to produce an armature, the windings in which will not fly out or explode when the armature is operated at comparatively high speeds.

A further object of the present invention is to wind an armature in such a manner that the conductors therein will be in substantial balance when the armature is rotated.

Further objects and advantages of the present invention will be apparent from the following description, reference being had to the accompanying drawings, wherein a preferred embodiment of the present invention is clearly shown.

In the drawings:

Fig. 1 is a diagrammatic view illustrating the cylindrical armature, its slotted body, commutator bars and windings all shown in a flat plane.

Fig. 2 is an end view of an armature produced in accordance with the present invention.

Fig. 3 is a similar view showing an armature constructed in accordance with standard practices.

Fig. 4 is an enlarged sectional view of the conductor containing, armature slot taken at the line 4—4 of Fig. 1.

Fig. 5 is a similar sectional view taken at the line 5—5 of Fig. 1.

The armature of the present invention consists of a shaft 120 upon which is mounted the body portion 121 of the armature and the commutator 122. The body portion 21 is laminated, preferably made up of a plurality of metal discs secured to the shaft 120 in stacked relation. A plurality of equally spaced radial slots 123 extend throughout the length of the body, the open ends of said slots being adapted to receive windings. All slots 123 have an insulating lining 124 of any suitable material. At the open end of each slot there are inwardly extending projections 125 and 126 providing a narrower slot opening in the surface of the armature body than the wire containing portions of the slot. A wire retaining peg 127, of any suitable insulating material, is inserted longitudinally into each slot, each peg having an enlarged head portion which fits into the wire containing portion of the slot beneath the projections thereof and having also a narrower body portion which fits into the narrower slot space between said two projections. The pegs in the slots are movable longitudinally of the slots but not radially, so that they form locking means preventing the wires from flying out of their respective slots when the armature is rotated, especially at high speeds.

2

The armature illustrated has 29 slots and 29 commutator bars, the latter being designated by the numerals 1 to 29 respectively. The coils of the armature each have 4 convolutions, one side of each coil being in one slot while the other side of the coil is in the seventh slot removed, thus providing 7 armature body segments therebetween. By following the heavy line winding A, such spacing may be noted. One end of this winding A is attached to commutator bar 1, while the other is attached to bar 15. Bar connection spacing for the other respective coils of the armature is similar.

Armatures have been produced by various methods, for instance, by introducing preformed coils into the body of the armature or by winding the conductor wires directly into the slotted body of the armature. Fig. 3 illustrates the one end of an armature, the windings of which were wound into the body of the armature by the regular method ordinarily used. This figure indicates a group of end loops at area 51 overlapping and lying upon the adjacent group at area 50. This not only produces unbalance as between the diametrically opposite areas 50—51 and 52, but also produces an armature subject to explosion especially at high speeds. By explosion it is meant that the unsupported, outside loop portions at the area 51 will loosen and fly outwardly at such high speed armature operation, the loosened winding loops rubbing against the field pieces in which the armature operates and thus causing severe damage to the electric machine.

Fig. 2 illustrates an armature produced by the improved method of this invention. Here the unbalance of the armature of Fig. 3 is completely eliminated inasmuch as substantial symmetry is maintained among the extending end loops arranged in a circular fashion about the armature shaft. The final seven end loops marked A to G are carefully folded over and drawn taut to embrace and securely hold adjacent loops underneath. These seven loops themselves are sufficiently tight to resist centrifugal force at substantially high armature speeds due to the fact that they come from beneath adjacent loops, are angularly folded over said adjacent loops, and, while drawn tight, placed into their respective slots, locked therein by an inserted peg and then securely attached to their respective commutator bars.

The usual method of winding an armature as illustrated by Fig. 3 is as follows: With one end of the wire secured to the proper commutator bar, the wire is placed in one armature slot, for instance a, then looped around the front end of

the armature placed in the second slot a' , then looped around the commutator or rear end of the armature and again placed in the said one slot. After the proper number of coil convolutions are placed in the slots, the final end extending from slot a' is extended toward the armature and then a locking peg is inserted in slot a' to hold the windings therein. The next adjacent coil is then wound in slots $b-b'$, the first end of the wire being secured to its proper commutator bar and the final end extending toward the commutator and being temporarily locked in slot b' by a peg inserted in said slot. Placement of the following coils in slots $c-c'$, $d-d'$, $e-e'$, etc., follows progressively in the same manner. When the position is reached at which the initial end of the coil (for instance AA) is to be placed, the peg, previously placed in slot a' , is removed as is also the final lap or end of the coil already placed therein. Then the coil AA, with its initial end wire secured to its proper commutator bar, is wound into its slots, the first of which is slot a' already containing the wires of coil A. After this coil AA is properly placed in its slots, the removed wire of the first coil is again placed in slot a' and then the peg is inserted in said slot. This method is followed for the placement of the following six coils BB to GG inclusive. Following this, the extending ends of all of the coils are secured to their respective commutator bars. By this well known and practiced method, an armature with a rear end as illustrated in Fig. 3 is produced. This method results in the arrangement of windings in slots a' and h as indicated by the Figs. 4 and 5 respectively. Slots a' to g' have the final end of the first wound coils therein on top of the other wire or coil ends therein while the remaining slots have their wires superposed in proper sequential order. In Fig. 4, the final sides of the coils appear superposed in the following manner: Coil A has its final sides arranged A^1 , A^2 and A^3 , then coil AA has its final sides arranged AA^1 , AA^2 , AA^3 and AA^4 and then the final side A^4 of the first wound coil is placed on top of the entire group in slot a' . In Fig. 5, the sides of the first coil are placed H^1 , H^2 , H^3 and H^4 and then the second coil is superposed as Q^1 , Q^2 , Q^3 and Q^4 or in sequential order.

The new winding method forming the subject matter of this invention is somewhat like that just described but differs therefrom when the final seven coils are to be wound into the armature. Just prior to the placement of coil AA, the first of the final seven coils, all pegs locking the final side of coils in slots a' to g' are completely removed. Then the final coil ends are also removed from said slots a' to g' and folded back out of the way of subsequent operations. Now the final seven coils AA to GG inclusive are placed in their respective slots, the first side of said coils being placed in slots a' to g' respectively. The starting end of these coils AA to GG are, of course, secured to their respective armature bars. After all of the coils AA to GG are placed and their final ends extended toward the commutator, the previously removed final sides of coils A to G are again placed in their respective slots a' to g' and then the locking pegs are inserted in said slots. As these final coil ends are replaced in their slots, they are carefully placed so that their loop ends at the rear of the armature lap over and embrace adjacent, underneath loops as illustrated in Fig. 2. The loose, projecting ends of the several coils are then attached to their respective commutator bars, thus the

stretching of the wires and particularly the final coil sides of the coils A to G, the locking of them in their slots by the pegs and the anchoring of them to their commutator bars all contribute to their ability to hold underneath loops securely and themselves to resist the exploding effect by centrifugal force when the armature is operated at substantially high speeds.

The important difference between the old method of armature winding herein described and the new method is that, by the old method, each final end or side of the first coil is taken from its slot, then the second coil side is wound therein, immediately after which the removed side of the first coil is replaced then locked therein by the replaced peg. This follows for each of the succeeding six coils finally placed. By the new method, all of the final sides of the first seven coils are removed from their slots and folded back. Then the final seven coils are wound, the first sides of said coils being placed upon the final sides of the initially placed coils in slots a' to g' . After the coils AA to GG are placed, then all of the removed final sides or ends of coils A to G are again placed in their respective slots a' to g' from which they were previously taken and then the locking pegs are inserted in all of the slots a' to g' . As before stated, the old method produces an armature as illustrated by Fig. 3, while the new method produces the better balanced and more securely locked together armature as illustrated by Fig. 2.

The aforescribed new method of placing windings in the slots of an armature as schematically depicted by Fig. 1 of the drawings may be reversed for the sake of assembly conveniences without sacrificing any of the advantages. For instance, the first placed coil may have its leading end attached to commutator bar 8, then laid into slot a looped over the end of the commutator body and laid into slot h and then looped back to slot a until the required number of convolutions are placed, after which a lock peg would be placed in slot h and the trailing end of the coil would extend toward the commutator. The next coil would be attached to bar 9, and would occupy slots g' and g . The loops in this particular mode of winding are wound counterclockwise as regards Fig. 1 whereas in the mode of operation as aforescribed, the coils are wound clockwise. Either way of winding provides the same results as regards the manner of loop fold at the front end of the armature to provide balance and end loop lock against throw out. In this last described modus operandi the treatment of the trailing ends of the first seven placed coils and the placement of the final seven placed coils in the particular design is exactly like that given in the first described operation.

Thus it may be seen that an armature produced in accordance with the present novel method is in substantial balance and substantially non-explosive when the armature is operated at high speeds. These advantages are attained without the use of added materials or longer assembling time. A mere change in the winding routine and method of placement of coil portions without added expense of material or time provide material advantages over the well known and practiced method of armature production.

While the embodiment of the present invention as herein disclosed, constitutes a preferred form, it is to be understood that other forms might be adopted.

What is claimed is as follows:

1. The method of winding an armature consisting of a shaft supporting a cylindrical body portion and a commutator, said body portion having a plurality of radial coil receiving slots extending longitudinally of and spaced equally around said body, said method consisting of the following steps; inserting a loop coil in a pair of predeterminately spaced slots with the leading end of the coil attached to a proper commutator bar, the trailing end extending from its slot toward the commutator; placing a locking peg longitudinally in the slot containing the trailing end of the coil; repeating this coil placement operation progressively around the armature by placement of coils in the predeterminately spaced pair of slots until the leading side of the coil next to be assembled will be placed in the slot containing the trailing end of the first placed coil at which time the peg in this last mentioned slot and the pegs in at least a majority of the slots up to the slot containing the leading convolution of said first placed coil are withdrawn, following which the respective trailing ends of the coils in the slots from which pegs have been withdrawn are also removed from said slots and bent back out of the way of the subsequent operation; then continuing with the placement of the coils whose leading ends are placed in the slots with pegs removed; then successively taking each bent back coil end, folding it over adjacent coil end loops, replacing it in the slot from which it was previously removed, inserting the peg into each slot after the final coil end has been placed therein, then drawing taut each loose trailing end of a coil extending from the armature body and securing it to the proper commutator bar.

2. A substantially balanced and unexplodable armature having a commutator and a body portion provided with radial slots extending longitudinally of said body portion, a plurality of loop coils placed in said slots, each coil having a leading end attached to a bar of the commutator and a trailing end attached to another bar of the commutator, the trailing and leading side convolutions of each coil being placed in pairs of predeterminately spaced slots in the armature body, each slot containing the leading side convolutions of one coil and on top of them the trailing side convolutions of the second coil, the final trailing convolutions of the initially placed coils, equal in number to the spacing of the slots occupied by a respective coil, having the leading sides of the finally placed coils superposed thereupon, the last placed trailing con-

volutions of said initially placed coils being folded over adjacent end loops of previously placed coils and inserted and locked in their respective slots on top of all the coil portions therein, said trailing ends of said initially placed coil convolutions being attached to their respective commutator bars; and a plurality of locking pegs insertable in said slots for securely holding the coil ends in loop supporting positions on the armature body.

5 3. The method of winding an armature consisting of a shaft supporting a cylindrical body portion and a commutator, said body portion having 29 coil-receiving slots and the commutator 15 a like number of conductor bars, the method consisting of the following steps; securing one end of a single wire conductor to a commutator bar then placing four convolutions of said wire conductor in two slots spaced with six slots 20 therebetween and letting the trailing end of the wire extend toward the commutator, placing a holding element in the slot containing the trailing end of the coil, repeating this coil placement operation progressively around the armature until the leading end of the coil next to be placed will occupy the slot already containing the trailing end of the first placed coil, removing the holding element in this last-mentioned slot and the holding elements in at least 25 four successive slots, then removing the trailing ends of the coils from the slots from which the holding elements have been removed and bending said trailing ends back out of the way to permit placement of the leading ends of coils 30 into said slots from which the said trailing ends have been removed, then successively replacing said bent back trailing coil ends into the slots from which they have previously been removed and inserting locking pegs in said slots, then 35 drawing said trailing, replaced ends taut and folding them over adjacent coil loops and securing the trailing ends of the coils to the proper commutator bars whereby the underneath coil ends are securely held against movement.
